UNITED STATES PATENT OFFICE.

ISAAC L. MARIENTHAL, OF CHICAGO, ILLINOIS, ASSIGNOR TO MODERN BELT CO., OF CHICAGO, ILLINOIS, A CORPORATION OF ILLINOIS.

DESIGN FOR A BELT-BUCKLE.

53,598.

Specification for Design.

Patented July 15, 1919.

Application filed February 24, 1919. Serial No. 278,989. Term of patent 3½ years.

To all whom it may concern:

Be it known that I, ISAAC L. MARIENTHAL, a citizen of the United States, residing at Chicago, in the county of Cook and State of Illinois, have invented a new, original, and ornamental Design for a Belt-Buckle, of which the following is a specification, reference being had to the accompanying drawing, forming part thereof.

view, and Fig. 3 is a perspective view, of the belt buckle.

I claim:

The ornamental design for a belt buckle as shown.

ISAAC L. MARIENTHAL.
